CLAIM

The ornamental design for an information retrieval device or similar article, as shown and described.

DESCRIPTION

FIG. 1 is a perspective view of an information retrieval device or similar article showing my new design;
FIG. 2 is a top plan view thereof;

FIG. 3 is a left end elevational view thereof;

FIG. 4 is a right end elevational view thereof;

FIG. 5 is a front elevational view thereof;

FIG. 6 is a rear elevational view thereof;

FIG. 7 is a bottom plan view thereof; and

FIG. 8 is a sectional view taken on line 8—8 of FIG. 2, with utilitarian internal structure shown as if homogeneous.
